[57] CLAIM

The ornamental design for a single door thread spool cabinet, as shown and described.

DESCRIPTION

FIG. 1 is front perspective view of a single door thread spool cabinet, showing my new design;

FIG. 2 is a top plan view thereof, the bottom plan view being a mirror image of the top plan view;

FIG. 3 is a front elevational view thereof;

FIG. 4 is a rear elevational view thereof;

FIG. 5 is an elevational view of one side thereof;

FIG. 6 is an elevational view of the other side thereof; and,

FIG. 7 is a front elevational view thereof but with the door in an open position to reveal the rows of spool-holding pegs.

FIG. 1.

FIG. 2.

FIG. 6.

FIG. 3.

FIG. 5.

FIG. 4.

FIG. 7.
